COMBINED CRADLE AND DISPLAY CABINET

Luther Shehan, P.O. Box 803, Spindale, N.C. 28160

Filed Feb. 21, 1975, Ser. No. 551,607

Term of patent 14 years

Int. Cl. D6—06

U.S. Cl. D6—4

FIG. 1

FIG. 3

FIG. 2

FIG. 4

FIG. 5

FIG. 1 is a perspective view looking at the top, end, and one side of a combined cradle and display cabinet and showing the display cabinet positioned in the cradle;

FIG. 2 is an exploded perspective view of the combined cradle and display cabinet;

FIG. 3 is a perspective view similar to FIG. 1 but omitting the display cabinet;

FIG. 4 is a perspective view similar to FIG. 3 but looking at the opposite end and side from that shown in FIG. 3; and

FIG. 5 is a rear elevation of the combined cradle and display cabinet.

I claim:

The ornamental design for a combined cradle and display cabinet, substantially as shown and described.
